UNITED STATES PATENT OFFICE.

LESTER E. CAMPBELL, OF MOBILE, ALABAMA.

METAL WHEEL BLOCK.

Application filed January 8, 1925. Serial No. 1,181.

To all whom it may concern:

Be it known that I, LESTER E. CAMPBELL, a resident of the city of Mobile, county of Mobile, and State of Alabama, and a citizen 5 of the United States, have invented certain new and useful Improvements in Metal Wheel Blocks, of which the following is a specification, reference being had to the accompanying drawing, forming a part 10 thereof.

My invention relates to wheel blocks for supporting pneumatic tired wheels in shipping or when for any reason it is desired to so support the tires that the weight of the 15 vehicle will be so distributed as not to bear wholly upon the portion of the tire in contact with the floor or ground. My invention has for its object to provide a wheel block for this purpose which may be formed of a 20 single strip of metal by bending, will be rigid and not to be distorted in use and will have at all points which can come in contact with the tire rounded surfaces.

With these and other objects hereinafter 25 explained in view my invention consists in the construction and combination of elements hereinafter described and claimed.

Referring to the drawings:

Figure 1 is a plan view of the sheet metal 30 blank from which my wheel block is formed.

Figure 2 is a view of the block from the front or higher end, partly broken away.

Figure 3 is a view of the block from the rear or lower end.

35 Figure 4 is a side view; and

Figure 5 is a perspective view of the block.

Figure 6 is a side view showing the blocks 40 in place with the wheel of the car resting thereon.

The blank from which the wheel block is formed comprises end or leg portions 1 and 2 and mid portion or tire supporting portion 3 forming together a strip of sheet metal. The end portions 1 and 2 are provided with longitudinal corrugations 4, 4. At their ends the end or leg portions 1 and 2 are each cut away at an angle of about 45 degrees and strips 5 and 6 at the ends 45 of the end or leg portions are turned outward at about right angles to the body parts of these end portions to form supporting feet. Along the edges of the body 50 part of the end or leg portions 1 and 2 narrow strips 7 and 8 are turned inward.

These inturned strips 7 and 8 are cut away on the lines on which the end strips are bent, the strips 7 along the longer edges of the portions 1 and 2 being cut at right angles as shown at 9 and the strips 8 along the shorter edges being cut on the line of the fold as shown at 10. The end strips are cut away on their ends near the strips 7 as shown at 11—12 and on their ends near the strips 8 are cut away as shown at 13. At 60 their ends adjacent the mid portion 3 the strips 7 and 8 are cut away at angles of about 45 degrees as shown at 14 and 15, the cuts being made at such distances from the ends of the mid portion 3 as to leave substantial intermediate portions 19 and 20 between the inner ends of the cuts and the adjacent end of the mid portion. 65

Strips 16 and 17 along the edges of the mid portion 3 are turned inward at right 70 angles. These strips 16 and 17 are cut away at their ends at right angles to the edges of the mid portion.

The blank being thus cut to shape and the ends 5 and 6 turned outward (or up) 80 and the edge strips 7, 8 of the end portions and the edge strips 16 and 17 being turned inward (or downward) the blank is ready to be bent to form.

The mid portion 3 is curved to the concave form shown in Figures 2, 3 and 5, the edge strips 16 and 17 following the concavity and serving to hold the mid portion rigidly in shape. The strips 7 and 8 being bent at right angles to the bodies of 90 the end portions 1 and 2 serve with the corrugations 4 to maintain these end portions rigid.

On the lines joining the mid portion 3 and the intermediate portions 19 and 20 the 95 metal is bent outward to a sharp angle as shown at 21 and from these lines the metal of the intermediate portions is bent inward so as to bring the angular ends 14 and 15 of the edge strips 7 and 8 against the under 100 face of the mid portion 3. The inwardly bent strips 7 and 8 thus serve to support the mid portion 3 and to prevent any tendency to break at the sharp bend 21. The reverse bend of the intermediate portions 19 105 and 20 brings the inner ends of the end portions 7 and 8 directly beneath the edges of the mid portion 3.

In the completed wheel block the side portions 1 and 2 flare outward at their lower 110

ends, and the ends 5 and 6 are bent outwardly at such angles that they will rest evenly on the floor.

The outward bend of the intermediate portions 19 and 20 is slightly curved so as to present a rounded surface and the edge strips 16 and 17 of the mid portion 3 are also so bent as to present rounded surfaces along their upper faces. The upper concave surface of the mid portion 3 is smooth and unbroken.

Having thus described my invention what I claim is:

1. A block for pneumatic tired wheels formed of a single strip of sheet metal comprising leg portions flaring outward at their lower ends provided with ends outwardly bent to form supporting feet and a mid portion concaved to receive the tire having end strips bent downward, the portion between the upper ends of the leg portion and the

mid portion being turned outward and folded inward upon itself so as to bring the upper edges of the leg portions beneath it.

2. A block for pneumatic tired wheels formed of a single strip of sheet metal comprising leg portions flaring outward at their lower ends provided with ends outwardly bent to form supporting feet and a mid portion concaved to receive the tire having end strips bent downward, the portion between the upper ends of the leg portion and the mid portion being turned outward and folded inward upon itself so as to bring the upper edges of the leg portions beneath it, the leg portions being provided with inwardly bent strips along their edges cut away at the upper ends to fit the under face of the concave mid portion.

In testimony whereof I hereunto affix my signature.

LESTER E. CAMPBELL.
